UNITED STATES PATENT OFFICE.

IRVING F. WEBB, OF ELIZABETH, NEW JERSEY, ASSIGNOR TO THE SINGER MANUFACTURING COMPANY, OF ELIZABETH, NEW JERSEY, A CORPORATION OF NEW JERSEY.

POWER-TABLE GUARD.

Application filed March 25, 1925. Serial No. 18,200.

To all whom it may concern:

Be it known that I, IRVING F. WEBB, a citizen of the United States, residing at Elizabeth, in the county of Union and State of New Jersey, have invented certain new and useful Improvements in Power-Table Guards, of which the following is a specification, reference being had therein to the accompanying drawings.

This invention relates to power-tables of the type commonly used in garment factories to support and drive a series of sewing machines. In a power-table installation each sewing machine of the series on the table is commonly belted to a respective treadle-controlled clutch-and-brake device known as a power-transmitter, the live element of which is belt-driven from a line-shaft running lengthwise of and below the table-top. The table-top is carried by a row of legs and the space lengthwise of the table between adjacent legs is known as a section.

The present invention has for an object to provide a simple, inexpensive and effective guard for the line-shaft, pulleys, belts and various moving parts below the table-top.

A further object of the invention is to provide a power-table guard which will meet the requirements of factory inspectors.

Still further, the invention has for an object to provide a power-table guard which may be readily shifted or removed from operative position, when desired, to afford access to the parts beneath the table-top.

To the attainment of the above and other objects, as will hereinafter appear, the present guard is preferably constructed in the form of a grid-like structure comprising end castings connected by a plurality of spaced parallel rods the length of which is substantially equal to the length of a section of the table. An intermediate arm through which certain of the full-length rods pass constitutes a support for one end of each of certain other rods which are shorter than the full-length rods and have their other ends supported by one of the end-castings. Mounted on the top-most one of the full-length rods adjacent the ends of the part-length rods is a transmitter-belt guard which may be adjusted lengthwise of or swung axially relative to its supporting rod. The transmitter-belt guard is preferably formed with an apertured boss through which its

supporting rod passes, a set-screw serving 55 to tighten the guard in effective position.

In the accompanying drawings, Fig. 1 is a front elevation of a section of a power-table with a guard embodying the invention. Fig. 2 is a fragmentary end elevation of the section shown in Fig. 1. Fig. 3 is a section on the line 3—3, Fig. 2. Fig. 4 is a section on the line 4—4, Fig. 2, and Fig. 5 is a perspective view of the guard removed from the power-table.

The power-table section illustrated comprises legs 1 and cross beams 2 carrying the table-top boards 3 which extend lengthwise of the table and on which are stationed the sewing machines, one of which is shown at 4. 70 Journaled in hangers 5 is the constantly running line-shaft 6 carrying the driving pulley 7 which is connected by the belt 8 to the live-element 9 of the power-transmitter or clutch-and-brake device, the driven element 10 of which is connected by the belt 11 to the balance-wheel 12 of the sewing machine 4. The power-transmitter includes the usual operating lever 13 to which the controlling treadle 14 is connected by means 75 of the treadle-rod 15. These parts are all of usual and well-known construction.

The power-table legs 1 are formed with co-planar inclined open-topped sockets or slideways 16 having bottom stop-walls or 85 rests 17. These slideways receive the co-planar lugs 18 of the end-member or castings 19, 20, of the present guard. The end-members 19, 20 have co-planar arms 21, 22, which carry a plurality of spaced horizontal rods 23 running substantially the full length of the section or space between the table-legs 1. The end-member 21 has an upward extension or arm 24 disposed at an angle to the arm 22. Mounted on the 90 rods 23 is an intermediate member having angularly related arms 25, 26, the latter being substantially parallel to the arm 24. One or more part-length rods 27 is or are carried by the arm 24 of an end-member and the arm 26 of the intermediate member. One of the full-length rods 23 passes through the apertured boss 28 of the transmitter-belt guard 29, set-screws 30 being 95 conveniently used for securing the guard 29 in operative or full-line position, Fig. 2, adjacent the transmitter-belt 8. The guard 29 may be readily shifted to dotted

line position to expose the belt 8 without removing the entire guard structure from operative position. Excessive end-play of the guard structure is prevented by means of the ribs 31 extending transversely of the slideways 16 adjacent the bottom-rests 17.

The entire guard structure may be removed as a unit by merely sliding it outwardly and upwardly through the upper 10 open ends of the supporting slideways 16 in the legs 1. The several horizontal rods 23, 27 of the guard are preferably secured in holes in their supporting arms by set-screws 32. The guard may also be removed 15 from the table by loosening the end-member 20 and sliding it on the rods 23 toward the intermediate member 25, 26, thereby withdrawing the lugs 18 from the socket or slideway 16. The guard may be shipped in 20 compact disassembled form and readily assembled into a rigid structure ready to place in the power-table.

Having thus set forth the nature of the invention, what I claim herein is:—

- 25 1. A guard for a power-table section comprising, a plurality of up-and-down supports and a plurality of horizontal rods carried by said supports, certain of said rods being of reduced length, and a transmitter-guard mounted on one of the full-length rods adjacent the end of a reduced length rod.
- 30 2. A guard for a power-table section comprising, a pair of end-members having sub-

stantially co-planar arms, one of said arms having an upward extension disposed at an angle to the plane of said arms, an intermediate member comprising angularly related arms, a plurality of full-length rods connected to said end and intermediate members, and one or more part-length rods 40 connecting the upper arm of said intermediate member to the upward extension of one of the end-members.

3. The combination with a sewing machine power-table including spaced supporting legs, a line-shaft and a power-transmitter, said legs being formed with downwardly and inwardly inclined guard-receiving sockets, of a shaft-guard removably fitted to said sockets, and a power-transmitter-belt guard carried by said shaft-guard and adjustable relative to the latter.

4. The combination with a sewing machine power-table having legs and guard-receiving sockets, of a guard including a plurality of end-members received in said sockets and a plurality of spaced horizontal rods carried by said end-members, one of said end-members being adjustable longitudinally of and relative to said rods to facilitate removal of the guard from operative position.

In testimony whereof I have signed my name to this specification.

IRVING F. WEBB.
